UNITED STATES PATENT OFFICE.

EDWARD W. CLARK, OF LOS ANGELES, CALIFORNIA, ASSIGNOR OF ONE-HALF TO
STANLEY S. TURNER, OF PASADENA, CALIFORNIA.

ADJUSTABLE CORE-BOX.

1,347,080.

Specification of Letters Patent. Patented July 20, 1920.

Application filed October 31, 1918. Serial No. 261,426.

To all whom it may concern:

Be it known that I, EDWARD W. CLARK, a citizen of the United States, residing in the city of Los Angeles, in the county of 5 Los Angeles and State of California, have invented new and useful Improvements in Adjustable Core-Boxes, of which the following is a specification.

My invention relates to core boxes, or 10 means for molding the interiors of hollow articles, and is particularly adapted for use in molding pistons for internal combustion engines, in which pistons of a minimum weight are preferable for use, the primary 15 object of this invention being to provide means for forming the cores so as to vary the character and dimensions of the pistons other than the diameter according to necessity, whereby the core mold may be stripped 20 from the core without damage to said core.

While there are relatively few standard diameters of pistons for internal combustion engines, there are a great many variations of 25 design for pistons of each standard diameter. Such variations include different dimensions from the pin centers to the head, the lengths of the piston skirt, that is the distance from the pin centers to the lower end of the pistons, the diameter of the pin 30 bearings, or bosses, some of the pins being fastened in the bearings of the pistons while others are loose therein, and thus requiring different size pin bosses. Also, some pistons have but a single ring groove while others 35 have two or more, and in some cases oil ring grooves are provided in the skirt of the piston for scavenging the cylinders during the operation of the engine. The number of 40 piston ring grooves thus requires additional thickness of metal at the head of the piston, and it is therefore, an object of my invention to provide a core box which may be readily adjusted to meet all of the above 45 named conditions and variations without the necessity of a different core box for each size and character of piston.

Some of the dimensions of a piston may be approximated but others must be exact, such as, for instance, the distance between 50 the pin centers and the head, and it is an object of my invention to provide a micrometer adjustment for determining and establishing this particular dimension.

Pistons of light weight being most desirable for use in internal combustion en-

gines, it is a further object of this invention to provide means in the core box for forming a plurality of annular reinforcing ribs in the skirt of the piston so as to provide against warping of the metal during 60 operation, and also a plurality of longitudinal ribs extending from the head down the interior periphery of the piston to the pin bearing bosses, thus reinforcing the head for the shock of the explosions, with the provision of means for forming annular and longitudinal rib recesses in the piston core. It will be obvious that when the mold is removed from the core, it must be done in such a manner that the composition and formation of the core body will not be disturbed, marred or damaged in any way, and a further object of this invention, therefore, is to provide means for stripping the rib 70 recess molding members from the core body 75 so as to remove the mold from the core without damage thereto.

A further object is to provide removable pin bearing bosses and common means insertible in the walls of the core box for supporting bosses of different diameter. Other objects will appear as the description progresses.

Referring now to the drawings, in which one form of my improved device is clearly 85 illustrated, Figure 1 is a side elevation of my improved core box, with the several elements assembled for use.

Fig. 2 is an elevation of the same at right angles to Fig. 1 and partly in section to 90 show the arrangement of the interior of the core box.

Fig. 3 is a fragmentary section of the core box on the line 3—3 of Fig. 5.

Fig. 4 is a fragmentary exterior view of 95 the same showing the micrometer head adjustment means.

Fig. 5 is a plan of the mechanism shown in Fig. 1, partly in section.

Fig. 6 is a bottom plan of the head forming means.

Fig. 7 is a section on line 7—7 of Fig. 5.

Fig. 8 is an elevation of a core made in my core box.

Fig. 9 is an elevation, partly in section of 105 a piston made by the use of the core shown in Fig. 8.

Fig. 10 is a horizontal section of the piston on the line 10—10 of Fig. 9.

Throughout the specification and in the 110

several views of the drawings similar characters of reference are employed for indicating the same and like parts.

As shown in the drawings, my improved core box comprises core print members P, skirt extension members E, annular wall members W and a head forming mechanism H, which when being assembled in their proper relation for use are arranged in the 10 manner shown in Fig. 1, one upon the other, with the print members P forming a support for the other members.

Members P, E and W are semi-circular in form and are adapted to be joined together at the center for forming a complete cylinder. Members P have diametrically opposite lugs 1, 1 which are adapted to be engaged when in position for use, and dowels 2, 2 are carried in one of each pair of said 20 lugs for insertion in the other lugs so as to properly center the members for use. Members W also have similar lugs 3 and dowels 4 for a like purpose, said lugs being positioned preferably above the pin centers.

25 The lower ends of members W have flanges 5, 5 formed thereon, between which and the tops of members P the extension members E are positioned and held by means of cap screws, or bolts 6 as shown in Fig. 1, and the 30 members E may be of a desired size for establishing a desired length of the skirt of the piston to be formed, thus varying the dimension between the pin centers and the tops of members P.

35 The exterior of members W may be finished, as shown, or not, as desired above and below the plane of the lugs 3, 3, but the interior of these members are designed to be finished as smoothly as possible so as to provide a smooth exterior for the core.

The interior 7 of members P has tapered sides so as to provide a proper draft for the core print P (see Fig. 8) which is formed therein, and an internal annular rib 45 8 is formed therein adjacent to the core print recess by means of which a corresponding annular groove 8' is formed in the core C, as shown in Fig. 8, and an internal annular rib 8'' is formed on the interior of the 50 piston p. Thus, the lower end of the completed piston p is reinforced against warping, due to the continual expansion and contraction of the metal during use.

The internal portion 9 of members P, E 55 and W forms the portions 9' and 9'' on the core C and piston p respectively. Where oil ring grooves, such as shown at 10 in the piston p, are desired, a ring 11 may be attached to the internal portion 9 of the skirt 60 by means of screws 11', as shown in Figs. 1 and 2, thus providing additional thickness of metal at a desired point in the piston wall.

At points slightly above and below the 65 pin positions of the piston annular shoul-

ders 12 and 13 are formed in the members W between which a slightly reduced internal portion 14 is formed in the members W and a corresponding external annular depression 14' is formed in the core C and piston p, and 70 said annular shoulders serve to reinforce the walls of the piston in the manner of an angle iron brace extending therearound, so that the metal of the walls may be reduced to a minimum.

75 Pin bearing supports 15 are provided in the members W and are positioned therein so as to be exactly opposite when said members are in position for use. These members have flanges 16 which rest against flattened portions 17 of the exterior of said members W and hubs 18 which are adapted to removably seat in bores 19 in members W. The pin centers of the core box are permanently fixed on said supports as hereinafter 80 described and the dimensions of the piston are measured above and below these centers. Bosses 20 are removably carried on the hubs 18 of said supports by means of screws 21. Bosses of different diameter may be attached 85 to the hubs 18 for use with different sized pins.

90 The upper ends of the members W are open so as to receive the head forming elements to be hereinafter described, and lugs 22 are formed thereon flush with the top which carry upwardly extending rods 23 fixed therein and also adjusting screws 24 which are threaded therethrough.

95 The head forming mechanism comprises 100 a pair of relatively movable members H¹ and H², member H¹ having an annular depending wall 25 which is designed to be finished on the inside and outside, the exterior periphery fitting into the upper end 105 of the cylinder formed by members W and the interior slidably receiving the member H².

110 Member H¹ has an annular flange 26 which is adapted to rest upon the upper ends of the adjusting screws 24, the turning of said screws in their supporting lugs 22 serving to adjust and limit the position of the annular wall 25 of member H¹ relative to the members W. The wall 25 of member H¹ when 115 in position in the upper end of the cylinder formed by members W registers with the ring groove section of the core box and provides additional thickness of metal at this point, such as shown at 25' in the piston p, 120 while a corresponding reduced end portion 25'' is formed on the core C.

125 Member H² has a core box end closing web 27 which closely fits the interior of wall 25 and an annular rib 28 is formed concentrically on the inner side thereof which in turn forms corresponding depressions in the core C and ribs 28' on the interior of the piston p. Radial ribs 29 connect the rib 28 with a central boss 30, by means of which the cor- 130

responding ribs 29' and boss 30' are formed on the piston *p*.

- Member H^2 has a vertically extended stem 31 formed integrally therewith which is slidably extended through a boss 32 on member H^1 and projects substantially thereabove, as shown, and to the upper end of this stem is attached a cross head 33 by means of a central screw 34, as shown in Fig. 1. Cross head 33 10 has bosses 35 at the opposite ends which are spaced to correspond to the spacing of rods 23, on the upper portions of which said bosses are adapted to be slidably held and locked for use by means of set screws 36. 15 An adjusting screw 37 is loosely extended through cross head 33 and is provided with a knurled head 38 thereabove, the lower end thereof being threaded into the hub or boss 32 of member H^1 and being provided with a lock nut 39 for locking said screw against movement after the same has been set at a desired point.

Cross head 33, during the setting up operation of the core box is loosely supported on the rods 23 and the set screws 36 are tightened only when the mechanism is entirely set for use in the core molding operation. A locking device is provided on cross head 33 for screw 37 and comprises a latch 40 held 30 on member 33 by means of a screw 41, a thumb piece 42 being provided thereon at one end and an extension 43 is formed on the other end for engagement with an annular groove 44 formed in the head of screw 37. 35 Thus the sliding movement of the cross head 33 on rods 23 and screw 37 may be prevented by the latching of the members 40 and 38. Rods 23 also are extended through flange 26 of member H^1 as shown so that said member 40 may be moved thereon.

A plurality of radially disposed grooves, or slots, 44', 44'', etc., are formed in member H^1 and extend inwardly from the periphery of flange 26 to points slightly inwardly of the periphery of the central boss 32, and in these grooves plates 45 and 46 are adjustably positioned for forming rib recesses 45' in the core C. The outer plates 45 are substantially narrower and longer than the plates 46 and screws 47 are threaded in the flange 26, the threads spanning the grooves therein, as shown in Fig. 7, so that the plates 45 and 46 may be held in said grooves by the pressure of said screws thereagainst. These plates 45 and 46 may be independently adjusted when the screws 47 are loose, plates 45 forming the wall rib recesses in the core and the lower ends of plates 46 forming the continuations of the head rib recesses for the formation of the ribs 29' on the piston, as shown in Fig. 9.

The plates 45 are preferably adjusted so that their lower ends are extended inwardly into the members W until said ends rest opposite the shoulder 12 while the lower ends 65 of plates 46 may be extended slightly below

the web of member H^2 . At diametrically opposite points aligned with the pin bearings, however, plates 45 and 46 are extended downwardly until their lower ends rest upon the upper portion of the pin bearing forming bosses 20, as shown in Fig. 2, so that the piston may be reinforced at these points for withstanding the strain and shock of the explosions against the head of the piston.

Cross head 33 has flanges 48 formed on the upper ends of bosses 35 by means of which the assembled core box may be supported in inverted position while the core is being formed therein. Clamps 50, of any suitable design may be employed for holding the members W together for use, as shown in Figs. 1 and 2.

In operation, the determined length of the piston skirt is established by inserting the extension member E of selected face width 85 between the members W and the core print forming member P and attaching the same thereto by means of the screws, or bolts 6.

The suitable size of the pin bearing bosses 20 having been determined, said bosses are 90 attached to the master boss supports 15 by means of screws 21, and the bosses then inserted in the openings of members W with the flanges 16 resting against the flat portions 17.

The members P, E and W are then properly positioned in their proper assembled relation and clamp 50 is placed in position for holding said members together, said clamp also serving to hold the pin bosses 15 100 in members W.

The number of rings and the width thereof of having been determined and the consequent amount of ring groove stock or metal at the head of the piston calculated, head 105 members H^1 and H^2 are adjusted by means of adjusting screw 37, member H^2 being slidably adjusted within the member H^1 and the distance from the lower face of member H^2 to the lower end of member H^1 being 110 measured as said members are adjusted for accurately setting said members in their proper relation, screw 37 being turned for such adjustment with head 38 thereof resting upon the upper surface of cross head 33 115 while the measurement is being taken. When the required adjustment is completed, screw 37 may be positively set by means of a lock nut 39 thereon and latch 40 may be turned so that the end 43 thereof will engage the 120 groove 44 of and lock head 38 of said screw. Screw 41 is then tightened so as to prevent the further accidental movement or displacement of the latch from the head of the adjusting screw. The assembled head comprising members H^1 and H^2 is then moved 125 downwardly on guide rods 23 until the flange 26 rests upon the ends of the screws 24, said screws being later adjusted and locked by means of nuts 37' for limiting the insertion 130

of the member 25 of member H¹ in the members W, for providing the ring stock for the piston.

In order to measure the required distance 5 between the pin centers and the top of the head, remove clamp 50 and also one of the pin bosses 15, insert a rule in the lower end of the core box and then measure down from the face of the head forming web of member H² to the center of the pin boss, the measurement on the rule being observed through the opening in member W from which the boss 15 was removed. Turn the adjusting screws 24 in the proper direction 10 for raising or lowering the head to obtain the exact determined distance desired and then tighten lock nuts 37', reinsert the pin boss 15, replace clamp 50 and tighten set screws 36 against rods 23, thus firmly holding 15 the body and head forming elements together for use.

The bracing and heat conducting rib forming plates 45 and 46 are next adjusted to their proper positions, the plates alined with 20 the pin bosses being moved downwardly until their lower ends rest upon the bosses 25 and thus provide in the core means for forming a maximum reinforcement and braces at these points extending from the head to said 30 bosses. Plates 46 at the other points project sufficiently into the core box to provide radial ribs on the inner surface of the piston head and also serve to take up and conduct the heat from the head. The remaining 35 plates 45 are extended downwardly along the inner periphery of members W for a desired distance for reinforcing the walls of the piston and the ribs formed on the piston by the core box thus molded not only reinforce 40 the walls but also serve as heat conductors and prevent undue expansion of the piston walls. While plates 45 and 46 are independently adjustable, they form single molding elements and single ribs are cast thereby, 45 and said plates are of such a length as to properly accommodate any length of piston. After adjustment, the plates are set and held by means of the set screws 47.

The core box, after the completion of the 50 foregoing operations is in readiness for use and may be inverted and supported on the flanges 48 of the cross head for filling with sand and the formation of the core therein. Upon the completion of the core, the core 55 box may be restored to initial upright position with the member P as a base therefor. Screw 41 of the latch is loosened and latch 40 turned from engagement with the head 38 of screw 37. Member H¹ is then raised 60 until further movement is prevented by its engagement with cross head 33, this operation also serving to strip the plates 45 and 46 from the core, thus preventing the marring or breaking of the core as the rib plates are 65 removed, and the said plates sliding up-

wardly through the slots or grooves in the member H². Member H² during the aforesaid operation rests upon the top of the core while the rib plates 45 and 46 and the wall forming member 25 are being withdrawn. 70 Screws 36 are next loosened and members H¹ and H² are bodily removed from the guide rods 23, said rods serving as guides for the head forming members until the same are entirely free from the core, thus 75 leaving a clean, smooth surface on the core. Clamp 50 is then removed and the pin boss members 15 are removed from members W, whereupon said members W may be withdrawn laterally, one at a time, thus freeing 80 the core entirely from the core molding elements.

My apparatus may thus be used for forming cores for pistons of different lengths and having different longitudinal dimensions 85 from the pin centers; also by varying the size and number of reinforcing ribs and providing pin bearings of different diameter; all of such varying characteristics being provided for in a single set of molds.

The foregoing description and the showing of the drawings pertain to and serve to disclose but a single form of my improvements and it is conceived to be possible to modify said disclosure within the scope of 95 the appended claims without departing from the spirit of my invention.

Having thus described my invention, what I claim as new and desire to secure by Letters Patent, is:

1. In a core box, a fixed body portion having members supported thereon for forming longitudinal recesses in the periphery of the core, and means supported on said body for extending the end portions thereof 105 relative to said members.

2. In a core box, a separable body, a core print forming member adjustably held on one end thereof, and an adjustable head forming member extensibly held on the 110 other end thereof and recess forming means carried on said head forming member, whereby the head and skirt portions of the core may be varied in length.

3. A core box comprising separable body 115 members one of said members being provided with internal annular reinforcing ribs, whereby corresponding grooves may be formed in the core and a removably held annular rib for forming an annular groove in 120 said core.

4. A core box having separable body members held together for forming a core therein, and removably supported internal means for forming an annular groove in said core. 125

5. A core box comprising separable body members for inclosing the sides of a core, a core print forming member extensibly held on one end of said body members, and an adjustable head forming member removably 130

- supported on and telescoping the other end thereof.
6. A core box for pistons and the like, comprising body molding means, an end 5 closing member supported thereon, and a plurality of blades slidably mounted in said end closing member and projected into said body molding means for forming rib recesses in the core and arranged for withdrawal 10 from the core previous to the removal of said body molding means.
7. A core box for pistons and the like, comprising body molding means closed at one end, said end having a plurality of radially formed slots therein and a plurality 15 of members slidably supported in said end and movable into and from the interior of said body molding means for forming peripheral recesses longitudinally of the core 20 and adapted to be withdrawn from the core previous to the removal of the body molding means therefrom.
8. A core box for pistons and the like, comprising body molding means closed at 25 one end, said end having concentrically and radiating ribs formed on the interior thereof for providing corresponding recesses on the end of the core, and means slidably disposed in said end for forming longitudinal 30 recesses on said core.
9. A core box comprising a separable body, a relatively adjustable member slidably supported in one end thereof, said member having an annular depending wall 35 adapted to form a corresponding reduction in the diameter of the core, and means for adjusting the relative positions of said adjustable member and said body.
10. A core box comprising a fixed body, a 40 core forming member slidably held on one end thereof, screw means for adjusting said member relative to said body, and means within and adjustable relative to said member for forming the head of the core.
- 45 11. A core box comprising a body, an annular core forming member slidably extended into one end thereof, screw means for adjusting said member relative to said body, and combined head and rib recess forming means adjustably carried by said member, for the purpose set forth.
12. A core box comprising a body, a combined head and wall forming element removably and slidably supported on one end 55 of said body, means for adjusting said element relative to said body, and means carried by said element for forming longitudinal recesses in the periphery of the core, for the purpose set forth.
- 60 13. A core box for piston cores and the like comprising a body for forming peripheral reinforcing rib recesses on the interior of the piston and at points opposite the ring grooves, and removable means for forming the head and longitudinal rib recesses.
14. A core box for casting pistons and the like comprising a body having a fixed central portion and extensible head and skirt portions for varying the dimensions relative to the center, and adjustable rib 70 forming means carried by said head portion.
15. A core box for pistons and the like, comprising body molding means closed at one end, means slidably supported thereon for forming longitudinal recesses on the periphery of the core, and means for limiting the movement of said recess forming means.
16. A core box for pistons comprising a separable body including a skirt forming portion, a head forming element extensible 80 thereinto, and means for adjusting said head element for making cores of different lengths from a single core box.
17. A core box for pistons comprising a body for forming the exterior of the core, 85 a head forming element for forming the head thereof, and a core print element extensibly held on said body, whereby cores of different length may be cast from a single core box.
18. A core box for pistons comprising relatively adjustable molding members for forming the head, body and print of the core, and means for adjusting and locking said members in fixed relation for use.
19. A core box for pistons and the like, comprising body molding means provided at the head with a wall of maximum thickness and at the skirt with a wall of minimum thickness, and means slidably disposed 95 in said body molding means for forming longitudinal rib recesses on the core.
20. A core box for pistons and the like, comprising body molding means having means thereon for reducing the diameter of 105 the head of the core, whereby additional thickness of metal may be provided in the piston in the casting operation, and means slidably disposed in said body molding means for forming rib recesses on the core.
21. A core box comprising separable body members, separable extension members attachable to said body members, and separable core print molding members attachable to said extension members, whereby the 115 length of a core may be changed as desired.
22. A core box for pistons and the like, comprising separable body molding members, an annular external core molding member supported on one end of said body molding members, and relatively movable head molding means, as set forth.
23. A core box for pistons and the like, comprising separable body molding members for forming the bottom of the core, a removable body molding member supported thereon for forming the top of the core, and relatively movable head molding means supported on said removable body molding member.

24. A core box for pistons and the like, comprising halved body molding members, a removable head molding member supported thereon and telescoping into said body molding members, and a core print molding member attachable to the opposite end of said body molding members. 70
25. A core box comprising separable body members capable of being held together for molding the body of the core, means for varying the length of the body formed thereby, and screw means for varying the distance from a fixed point on said body to and forming the head of the core. 75
26. A core box comprising a pair of laterally separable body molding members and longitudinally adjustable end forming members removably carried by said body members. 80
27. A core box comprising a pair of laterally separable body molding members, a core print molding member, extension means for said core print forming member, and relatively adjustable head molding means, 25 as set forth. 85
28. A core box having separable sides and relatively adjustable ends, whereby cores of a given diameter and different lengths may be formed with a single core box. 90
29. A core box for pistons comprising a fixed body molding member, and a relatively adjustable telescoping member supported thereon for regulating the distance between the head and skirt, as set forth, whereby cores of different length may be formed. 95
30. A core box comprising a body molding member, a wall molding member telescoping thereto and adjustable end molding means carried by said wall molding means, for 40 forming cores of different lengths from a single pattern. 100
31. A core box comprising a body molding member, a wall molding member slidably supported in said body molding means, and an end molding means slidably supported in said wall molding means, as set forth. 105
32. A core box comprising a main body molding member, a wall molding member adjustably supported thereon, means for adjusting said wall molding member relative to said body member, an end molding member adjustably supported in said wall molding member, and means for adjusting said end member and locking the same for use. 110
33. A core box comprising a body molding member, a relatively adjustable wall molding member telescoping thereto, an end closing member slidably carried by said wall molding member, means for adjusting said members for use, and means for permitting an independent movement of said wall and end members relative to said body, for releasing the core. 120
34. A core box comprising relatively adjustable body, wall and end molding mem- 65 bers, means for adjusting and locking said members for use, and means whereby when unlocked, said wall and end members may have a movement independent of said body for removing the same from the core. 130
35. A core box comprising relatively adjustable body, wall and end molding members, means for adjusting and locking said members for use, and a plurality of rib molding elements carried by said wall and end molding members, as set forth. 70
36. A core box comprising body, wall and end molding members relatively adjustable for use, and a plurality of rib molding elements supported in said wall and end molding members as set forth. 80
37. A core molding device for pistons and the like including a skirt molding element, a relatively stationary head molding element, and a stripping element movably disposed relative to said skirt and head molding elements, for freeing the core from the mold. 85
38. A core molding device comprising a skirt molding element, a relatively stationary head molding element, a stripping element movable relative to said skirt and head molding elements, and a plurality of blades carried in said stripping element for forming recesses in the core. 90
39. A core molding device comprising a body molding element, a relatively stationary head molding element adjustable to different positions relative to said body molding element, and a stripping device movable relative to said body and head molding elements. 95
40. A core molding device comprising a body molding element, a head molding element on one end thereof, a guide supported on said body molding element and adapted to hold said head element centrally in said body, a movable member on said guide, and means carried on said movable member and capable of extension through said head molding element for forming longitudinal recesses on the core. 100
41. A core making device including a combined end and peripheral molding member having relatively stationary and movable elements, and means for limiting the movement of said movable member, as set forth. 110
42. A core making device having a stripping mechanism comprising relatively stationary and movable elements, portions of said movable element extending through said stationary element, whereby the mold may be stripped from the core without damage thereto. 120
43. A core box having a stationary body and a plurality of blades normally extended into the interior of said body and adapted to be retracted therefrom for freeing the mold from a core. 125
44. A core mold comprising a body, the

interior of which conforms to the interior of the article to be molded, rib-recess forming elements or blades removably held therein for forming ribs on the interior of said article, whereby said rib-recess forming elements can be withdrawn without disturbing the sand core formed in said mold.

45. A core mold comprising a body, the interior of which conforms to the interior of 10 the article to be molded, rib-recess forming elements or blades adjustably and removably

held therein for forming ribs in the interior of said article, whereby said rib-recess forming elements can be withdrawn without disturbing the sand core formed in said mold. 15

Signed at Los Angeles, in the county of Los Angeles and State of California, this 23d day of October, 1918.

EDWARD W. CLARK.
